Primary Examiner—B. J. Bullock*Assistant Examiner*—Stacia Sinuik*Attorney, Agent, or Firm*—Christie, Parker & Hale, LLP**[57]****CLAIM**

The ornamental design for a vehicle wheel front face, as shown and described.

DESCRIPTION

FIG. 1 is a front perspective view of a vehicle wheel front face according to my new design; and,
FIG. 2 is a front elevational view thereof.

The broken line showing of the wheel is for illustrative purposes only and forms no part of the claimed design.
